UNITED STATES PATENT OFFICE.

CHARLES WRIGHT, OF EVERSON, PENNSYLVANIA.

DRAW-GEAR FOR CARS.

SPECIFICATION forming part of Letters Patent No. 701,660, dated June 3, 1902.

Application filed May 31, 1901. Serial No. 62,648. (No model.)

To all whom it may concern:

Be it known that I, CHARLES WRIGHT, a citizen of the United States, residing at Everson, in the county of Fayette and State of Pennsylvania, have invented new and useful Improvements in Draw-Gear for Cars, of which the following is a specification.

The object of my invention is, first, the provision of means whereby the coupler or coupler and spring mechanism of a draw-gear can be raised or lowered, so that the center line of the coupler-head will occupy a certain predetermined position relative to a plane passing through the top surfaces of the rails of the track upon which the car moves.

The interstate commerce law requires that the height of draw-bars upon cars used in interstate commerce shall be substantially uniform. It has been recognized as a difficult problem to meet the requirements of the law, inasmuch as a car after being in service for a time sags or settles down and causes the coupler to occupy a position below the required height. The method commonly followed when the coupler occupies too low a position is to insert blocks or shims between certain parts of the truck or between the truck and body-bolster, thus raising the car-body and the coupler along with it. Ordinarily the shims last but a short time, when they must be replaced, which operation entails much expense and labor. Now I think I have satisfactorily solved the problem of easily maintaining the draw-bar at the standard height and by providing means for raising or lowering the coupler or coupler and spring mechanism relative to the car-body and without resorting to the readjustment of the car-body relative to the trucks.

The further object of my invention is the improvement of the spring buffering and drawing mechanism and adapting it for use with heavily-loaded cars.

With the above-recited ends in view my invention consists, objectively, in a draw-gear which can be bodily raised and lowered relative to the car-body proper.

Further, it consists in a draw-gear the coupler-head of which can be raised and lowered relative to the car-body and without detaching the same from the spring draft and buffering mechanism.

Finally, it consists in certain novelties of

construction and combinations and arrangements of parts hereinafter set forth and 55 claimed.

The accompanying drawings illustrate an example of the physical embodiment of my improvements constructed according to the best modes I have so far devised for the practical application of the principles.

Figure 1 is a side view in elevation of the coupler and spring mechanism of a draw-gear, showing one of the stay-plates, the cast-steel blocks, a side spring, the ends of the followers, and shims or plates. Fig. 2 is a longitudinal section of Fig. 1, taken in a plane parallel with the shank of the coupler and between the longitudinal stringers. Fig. 3 is a bottom plan view of Fig. 1, also showing the 70 carry-iron broken away and disclosing the notch in the stay-plate for the removal of the shims. Fig. 4 is a section of Fig. 1. Fig. 5 is a view of one of the shims, which are located beneath the shank of the coupler. Fig. 75 6 shows the rear follower. Fig. 7 is a view of one of the pin-supporting blocks.

Referring to the several figures, the letter A designates the central stringers of the car-frame, which may be of wood or metal. 80

B is the end sill; C, a body-bolster.

D indicates filling-pieces back of the bolster, which may be of any length, extending from bolster to bolster when so desired.

E is the coupler of any approved type; F, 85 the yoke or spring-pocket, which is bent to a round shape at the end.

G indicates stay-plates, each made by bending a steel or iron plate which is about one-half inch by six inches upon itself, so as to 90 form a pocket, the lower portion extending back of the bolster and the upper portion extending at least to the bolster, as clearly shown by the drawings.

H is a carry-iron; I, a strap plate or tie. 95

J indicates front malleable or cast steel or wood blocks, made in any desirable way, as with ribs or cored out to secure requisite strength and lightness and located between the upper and lower portions of the stay- 100 plates G and at the front ends thereof.

J' indicates rear malleable or cast steel or wood blocks located within the pockets and adjacent the body-bolster, and they may be of the shape shown or of any other shape. 105

K indicates flanges formed integral with

each of the blocks J and J', said flanges in this case being one inch thick and two inches deep.

5 L indicates metallic blocks, each being two inches by four inches by six and one-fourth inches and having a two-inch hole, the said blocks being located at the ends of the blocks J and J' and adjacent the flanges K and likewise flush with the edges thereof.

10 M indicates perforated outside removable plates which secure the blocks L within the pockets; N, bolts which pass through the plates M and blocks J and J' and secure the said plates M in their removable positions.

15 O indicates twelve bolts which pass through the central stringers, the blocks J and J', the stay-plates, and the filling-pieces in the rear of the body-bolster.

P indicates pins which have their ends seated within the holes of the blocks L and by them are held against displacement.

20 Q indicates the outside springs, which may be single or double, as shown, surrounding the pins P and held by them in line.

25 R is the central spring or springs, located within the yoke F of the coupler.

S is the front follower, slotted at the ends and supported by the pins P and the yoke.

30 T is the rear follower, also having slotted ends and an enlarged semicircular bearing, which fits the inner curved surface of the end of the yoke.

U indicates steady pins or lugs on the followers which hold the spring or springs in place.

35 V indicates shims or plates, shown as located beneath the followers, the blocks L, and the outside springs.

W indicates the shims or plates, which are 40 shown as located beneath the shank of the coupler, the said shims being cut away at the ends and of the general shape illustrated by Fig. 5 of the drawings, and X is a notch in one of the stay-plates, which allows the removal of the shims when one end of the carry-iron has been detached.

The method of assembling the several parts is obvious from the drawings and need not be specifically set forth.

50 The shims or plates V and W are the means by which the coupler-head or the draw-bar and spring mechanism can be raised and lowered relative to the car-body proper and so that the coupler-head will occupy the required position above the rails. In the drawings the plates are all below the coupler and spring mechanism. Any number or all of these plates can be taken out and placed above the draw-bar and followers, thus lowering the draw-bar and spring mechanism.

55 To do this, the plates M are taken off and the carry-iron disconnected at one end and displaced from its normal position over the notch X in the stay-plate. In connection with a draw-gear eleven inches deep the coupler and spring mechanism can be raised or lowered five inches, and with a gear nine

inches deep an adjustment of three inches is possible. The plates under the shank of the coupler should be of metal and those under the followers of metal and wood or any other material, as desired.

60 From the foregoing description, taken in connection with the drawings, it is clear that I have provided a draw-gear which fulfills all the 75 conditions set forth as the objects of my invention. Means for raising and lowering the coupler and spring mechanism is disclosed, which is simple in construction and which can easily and quickly be manipulated, and a spring drawing and buffering mechanism is disclosed, which has ample spring capacity and strength to withstand all strains to which it may be subjected in use upon heavy cars or those which are heavily laden.

75 While I have illustrated and described only one example of means for raising and lowering the coupler or coupler and spring mechanism relative to the car-body and one example of the spring drawing and buffering 90 mechanism, I do not thereby intend to limit the scope of my invention to the said specific examples, inasmuch as my improvements can be physically embodied by other modes of applying the principles and by other examples without constituting a substantial departure. Modifications, substitutions, alterations, and manifold changes may be introduced at will, which will fall within the limits of my invention and the scope of the claims.

100 What I claim as new, and desire to secure by Letters Patent, is—

1. The combination with a car-body and a coupler, of a plurality of removable shims or plates W located above the carry-iron for adjusting the head of the coupler in a vertical plane and relative to the car-body.

105 2. The combination with a car-body and a coupler and a spring mechanism, of a plurality of removable shims W and V for adjusting the coupler and spring mechanism vertically relative to the car-body.

110 3. The combination with a car-body and a coupler, of a plurality of removable shims or plates for adjusting the head of the coupler in a vertical plane and relative to the car-body.

115 4. The combination with a car-body and a coupler and spring mechanism, of a plurality of removable shims or plates for adjusting the coupler and spring mechanism vertically relative to the car-body.

120 5. The combination with a car-body and draw-gear, of means for adjusting the draw-gear vertically relative to the car-body, said means being located beneath the ends of the follower or followers and supporting the same.

125 6. The combination with a car-body and coupler head and shank, of means for adjusting the coupler head and shank vertically relative to the car-body, said means consisting of a plurality of shims or plates located between the carry-iron H and the shank, and some or all of said shims adapted to be removed and placed above the shank so as to

confine the shank and prevent the upward and downward movements of the coupler-head in buffing.

7. The combination with a car-body, coupler, spring mechanism, and follower or followers, of means for adjusting the coupler and spring mechanism and a follower or followers vertically relative to the car-body, said means being located under the follower or followers, and also under the shank of the coupler adjacent its head.

8. The combination with a car-body, of a coupler having a yoke; two followers located within the yoke; springs between the followers; and a plurality of shims for adjusting the coupler-yoke, followers, and springs in a vertical plane.

9. The combination in a draw-gear, of a coupler; central stringers; stay-plates secured to the stringers and forming pockets; front and rear malleable or cast-steel blocks within the pockets; springs located between the blocks; and two followers engaging the springs at their ends and adapted to be moved by the coupler.

10. The combination in a draw-gear, of a coupler; two stay-plates; two followers slotted at the ends; four metallic blocks located between the upper and lower parts of the stay-plates; two springs supported by pins which engage the followers; and removable plates, M, whereby the springs can be removed without displacing the coupler or followers.

11. The combination with a draw-gear constructed substantially as set forth, of stay-plates, G, each made by bending a piece of metal upon itself and forming pockets for metallic blocks and against which the followers bear in towing and buffing.

12. The combination with a draw-gear, constructed substantially as set forth, of springs, Q, supported by pins, P, which engage blocks, L, said blocks L bearing against the blocks J and J', which latter are located between the stay-plates G, G, as set forth.

13. The combination with a draw-gear, embracing a coupler and followers and constructed substantially as set forth, of two stay-plates, each stay-plate supporting a front and a rear metallic block and each block having a flange, K; blocks, L, located adjacent the flanges K; pins, P; removable plates, M; followers, S and T; and springs supported by the pins.

14. The combination in a draw-gear of stay-plates G; a coupler, and a coupler-yoke curved at the end; two followers slotted at the ends and one of the followers having a curved surface; pins P; springs; blocks J J'; and removable plates M.

15. The combination with a draw-gear and shims for adjusting the coupler, of a stay-plate cut away at X to allow the removal of the shims W, and a carry-iron which normally retains the shims in position by closing the opening formed by cutting away the stay-plate.

16. The combination with a draw-gear, of a plurality of shims, V, and removable plates, M, whereby the shims can be removed and replaced.

17. The combination with a draw-gear, of stringers; stay-plates under the stringers; metallic blocks located directly beneath the stringers and within the stay-plates; followers engaging the blocks; and springs engaging the followers at their ends.

18. The combination with a draw-gear, constructed substantially as set forth, of stay-plates, each plate made by bending a metallic plate upon itself to form a pocket; follower-plates; metallic blocks located at the ends of each pocket; and springs located between the follower-plates at the ends of the blocks.

19. The combination with a draw-gear, constructed and operating substantially as set forth, of springs, Q; means for holding the springs in place; followers, S and T; and a plurality of plates or shims, V.

20. The combination in a draw-gear, of a coupler; a yoke secured to the coupler; followers notched at the ends; pins P which guide the followers; springs Q upon the pins P; spring R located within the yoke; blocks J J'; stay-plates G G embracing the blocks J J'; removable plates secured to blocks J J' which allow the removal of the springs Q at the sides; and bolts securing the stay-plates to the central stringers.

21. The combination with a draw-gear, constructed substantially as described, of stay-plates G G; blocks J J' supported by the stay-plates and bolts O; blocks L L located at the ends of blocks J J'; pins P supported by blocks L L; springs Q Q on the pins; two followers engaging the pins; a coupler; a coupler-yoke; and removable plates M M; as set forth.

22. The combination with a draw-gear, of stay-plates located directly under the central stringers; blocks secured in position beneath the stringers and between the upper and lower portions of the stay-plates; springs located directly under the stringers and in line therewith; a coupler; followers engaging the springs; and means uniting the coupler-shank and the followers.

23. The combination in a draw-gear, of the central stringers A A; stay-plates each having an upper horizontal portion parallel with and adjacent a stringer and a lower portion parallel with the upper portion and located in a lower horizontal plane; blocks between the upper and lower portions of the stay-plates; and bolts passing through the stringers, the upper and lower portions of the stay-plates, and also through the blocks.

In testimony whereof I affix my signature in presence of two witnesses.

CHARLES WRIGHT.
